UNITED STATES PATENT OFFICE

173,309

ELECTRONIC ORGAN

Joseph M. Johnston, Bradley Beach, N. J.

Application April 20, 1954, Serial No. 30,103

Term of patent 14 years

(Cl. D56—2)

To all whom it may concern:

Be it known that I, Joseph M. Johnston, a citizen of the United States of America, residing at Bradley Beach, in the county of Monmouth and State of New Jersey, have invented a new, original, and ornamental Design for an Electronic Organ, of which the following is a specification, reference being had to the accompanying drawing, forming a part hereof.

The drawing figure is a perspective view of an electronic organ embodying my new design.

I claim:

The ornamental design for an electronic organ, as shown.
